UNITED STATES PATENT OFFICE.

ALFRED L. GLOVER, OF REVERE, MASSACHUSETTS.

OFFICE-ROSTER.

1,033,096.

Specification of Letters Patent. Patented July 23, 1912.

Application filed June 28, 1911. Serial No. 635,747.

To all whom it may concern:

Be it known that I, ALFRED L. GLOVER, a citizen of the United States, residing at Revere, county of Suffolk, Commonwealth 5 of Massachusetts, have invented certain new and useful Improvements in Office-Rosters, of which the following is a specification.

This invention relates to office rosters or similar devices in which lists of names or 10 like items which are subject to change are displayed.

In modern use this class of device has become very generally employed and particularly in such instances as the use in large 15 office buildings the possibility of keeping such a roster correctly posted is of the utmost importance. One of the great difficulties in keeping such a roster corrected to date lies in the trouble involved in substituting the elements which bear the names.

It is the object of the present invention to provide a device of cheap and simple construction in which the unit elements may be quickly and easily placed and replaced.

25 To this end, therefore, the invention contemplates a structure in which unitary strips are employed and so mounted as to be capable of easy and immediate engagement by the fingers, while ordinarily lying perfectly flush and uniform with regard to each other. The fundamental principle involved 30 is the supporting of a plurality of removable resilient strips in such a way as to permit their relative depression to afford possibility of engagement.

The construction and use of the invention will be more fully described in the specification which follows. In that specification and in the drawings which form a part of 40 it there is described and shown a particular form of construction which is found to be especially well adapted to practical use.

Throughout specification and drawings like reference numerals are employed to indicate corresponding parts and in the drawings:—

Figure 1 is a view of a roster with the case door open. Fig. 2 a section on the line 2—2, Fig. 1, Fig. 3 a detail of one of the 50 spring unit strips, Fig. 4 a sectional longitudinal section on the line 4—4, Fig. 1, and Fig. 5 a view of the lower part of the frame showing the method of engaging a strip.

The device is preferably constructed as a case comprising a back 1 surrounded by side 55 strips 2 to which is swung a door frame 3 by hinges 4. Within the side strips 2 and mounted on the backing 1 are small vertical metal channel strips 5, strips 6 mitered thereto and held in place by blocks 7 and 60 having a central vertical channel strip 8. Upon the side strips 5 are mounted flanges 11 forming vertical grooves on each side of the frame. It will, therefore, be seen that there are left between the strips 5 and the 65 central strip 8 spaces 9.

10 are unit strips which are preferably made of ordinary spring steel stock cut off at suitable length to fit horizontally between the flanges 11. These strips are preferably 70 enameled black or some such suitable color and on them is placed the desired information, as for example the names and room numbers of the occupants of office buildings.

When it is desired to fill a roster the strips 75 are prepared with the proper names and by slightly bending each strip 10 the whole vertical length of the roster is filled up with the ends of the strips 10 engaged beneath the flanges 11. The roster in Fig. 1 is not 80 shown completely filled. This, however, is merely done to expose part of the frame and in actual use the roster would always be completely filled so as to present a complete surface concealing the structural part of 85 the device. If there are insufficient names upon the roster to do this blank strips are put in in the usual manner. When now it is desired to remove one of the strips and replace it with another one the strips on 90 each side of the one to be removed are depressed by thumb and forefinger, as indicated in Fig. 5. This exposes the edge of the strip to be removed which may be then grasped and pulled upon. This will bend 95 the strip sufficiently to shorten it and disengage it from the flanges 11. A similar result may be obtained by pressing upon the strip to be removed at one side of the center bar 8. This depression upon one side will 100 cause a corresponding elevation of the strip on the opposite side of the center bar 8 and the strip may be then engaged as above described.

Various modifications may be made in the 105 construction and use of the invention, all

without departing from the spirit thereof if within the limits of the appended claim.

What I, therefore, claim and desire to secure by Letters Patent is:—

5 In a device of the class described, a vertical frame having lateral channels, an intermediate support leaving spaces between said support and said channels and a plurality of removable flexible strip units dis-

posed with their ends within said channels 10 and depressible within said spaces.

In testimony whereof I affix my signature in presence of two witnesses.

ALFRED L. GLOVER.
